(57) **CLAIM**

We claim the ornamental design for a device harness, substantially as shown and described.

DESCRIPTION

FIG. 1 is a perspective view of a device harness in accordance with the present design.

FIG. 2 is a top view of the device harness.

FIG. 3 is a bottom view for the device harness.

FIG. 4 is a front view for the device harness.

FIG. 5 is a rear view for the device harness.

FIG. 6 is a right side view for the device harness.

FIG. 7 is a left side view for the device harness.

FIG. 8 is an exploded front view for the device harness, shown in its environmental use.

FIG. 9 is a front view for the device harness; and,

FIG. 10 is a perspective view of the device harness.

The broken lines showing of an electronic device, cord and other elements are for illustrative purpose only and form no part of the claimed design.
